(57) **CLAIM**

The ornamental design for a motorcycle muffler, as shown and described.

DESCRIPTION

FIG. 1 is a front elevational view of a motorcycle muffler showing my new design;

FIG. 2 is a rear elevational view thereof; and

FIG. 3 is a left side view thereof;

FIG. 4 is a right side view thereof;

FIG. 5 is a top plan view thereof;

FIG. 6 is a bottom plan view thereof;

FIG. 7 is a perspective view of a motorcycle muffler showing my new design;

FIG. 8 is the second perspective view thereof; and,

FIG. 9 is the third perspective view thereof.

The broken lines in the figures are for the purposes of illustrating portions of the motorcycle muffler, which form no part of the claimed design.

1 Claim, 9 Drawing Sheets
